H. B. GILLETTE

WHEEL

Filed May 24, 1924

INVENTOR

Herbert B. Gillette

BY *Chappell Teare*
ATTORNEYS

UNITED STATES PATENT OFFICE.

HERBERT B. GILLETTE, OF GRAND RAPIDS, MICHIGAN.

WHEEL.

Application filed May 24, 1924. Serial No. 715,575.

To all whom it may concern:

Be it known that I, HERBERT B. GILLETTE, a citizen of the United States, residing at Grand Rapids, county of Kent, State of Michigan, have invented certain new and useful Improvements in Wheels, of which the following is a specification.

This invention relates to improvements in wheels.

10 My invention relates more particularly to improvements in wheels adapted for use on trucks although desirable and capable of various other uses.

15 The main objects of this invention are:

16 First, to provide an improved wheel which is very strong and durable and at the same time substantially noiseless.

20 Second, to provide an improved wheel which may be effectively formed of waste cuttings of wood.

Third, to provide an improved wheel which may be rapidly and economically manufactured.

25 Further objects, and objects relating to structural details, will definitely appear from the detailed description to follow.

I accomplish the objects of my invention by the devices and means described in the following specification. The invention is 30 clearly defined and pointed out in the claims.

A structure which is a preferred embodiment of my invention is clearly illustrated in the accompanying drawing, forming a part of this application, in which:

35 Fig. I is a side view illustrating one of the steps in the manufacture of my improved wheel.

40 Fig. II is a detail section on a line corresponding to line 2—2 of Fig. III, showing further structural details.

Fig. III is a detail section on a line corresponding to line 3—3 of Fig. I.

Fig. IV is a side elevation of a completed wheel.

45 Fig. V is a detail section on a line corresponding to line 5—5 of Fig. IV.

In the drawing similar reference characters refer to similar parts throughout the several views, and the sectional views are taken looking in the direction of the little arrows at the ends of the section lines.

50 Referring to the drawing, my improved wheel comprises an annular body portion formed of radially disposed blocks of wood, the embodiment illustrated consisting of the wedge-shaped blocks 1 and the rectangular

blocks 2, there being a pair of wedge-shaped blocks between each pair of rectangular blocks.

The blocks have registering bores or holes 30 30 therein which form a continuous annular bore, there being a hole 4 in one of the blocks communicating with this annular bore so that molten metal, such as babbitt or the like, may be poured through the hole and is cast or molded into a ring 5 thereby providing an internal metal ring binding the blocks together. Previous, however, to the casting of the ring 5, the blocks are clamped up by means of the clamping band 6 having ears 7 70 at the ends thereof through which the clamping bolt 8 is disposed.

After the blocks are thus secured together, they are machined to provide the outwardly facing shoulders 9 on which the annular side 75 plates or rings 10 are secured by means of the rivets 11.

It will be observed that the ends of the blocks project beyond the outer edges of the clamping rings, the ends of the blocks constituting the tread of the wheel.

The hub 12 is secured in any suitable manner and as effective means are well known in this art, such means are not illustrated.

80 My improved wheel is very strong and 85 rigid and is capable of carrying heavy loads and withstanding severe racking strains. It is designed to be used without a tire so that it is substantially noiseless when employed on cement floors or pavements. 90

The wheels are made of small pieces of wood which are ordinarily regarded as waste in factories.

95 The blocks 1 and 2 may be rapidly formed by sawing or slicing operations.

Having thus described my invention, what I claim as new and desire to secure by Letters Patent, is:

1. In a wheel structure, the combination 100 of a plurality of wedge-shaped blocks and a plurality of rectangular blocks disposed radially, there being a pair of the wedge-shaped blocks between each pair of rectangular blocks, said blocks having annular registering shoulders on their outer sides 105 and having registering holes therein providing a continuous annular bore, a ring of metal cast in said annular bore, and clamping rings upon the sides of the blocks in engagement with said shoulders. 110

2. In a wheel structure, the combination of a plurality of wedge-shaped blocks and a

- plurality of rectangular blocks disposed radially, there being a pair of the wedge-shaped blocks between each pair of rectangular blocks, said blocks having registering holes therein providing a continuous annular bore, and a ring of metal cast in said annular bore.
3. In a wheel structure, the combination of a plurality of blocks disposed radially to provide an annular unit, said blocks having annular registering shoulders on their outer sides and registering holes therein providing a continuous annular bore, a ring of metal cast in said annular bore, and clamping rings 15 upon the sides of the blocks in engagement with said shoulders.
4. In a wheel structure, the combination of a plurality of blocks disposed radially to provide an annular unit, said blocks having registering holes therein providing a continuous annular bore, and a ring of metal cast in said annular bore. 20
5. A wheel unit comprising wedge-shaped blocks of wood disposed radially and intermediate blocks of wood with parallel sides 25 disposed between said wedge-shaped blocks, said blocks having registering holes providing an annular bore within the blocks, and a metal ring cast within said bore.

In witness whereof I have hereunto set 30
my hand.

HERBERT B. GILLETTE. [L. S.]
